TEMPLLET

Alexander P. Stewart, Detroit, Mich.

Application September 12, 1938, Serial No. 229,550

1 Claim. (Cl. 90—62)

My invention relates to a new and useful improvement in a templet adapted for use on profiling or duplicating machines. A satisfactory method of producing such templets is to form the same from a plastic material and allow the material to harden. It has been discovered, however, that frequently a sheet of metal is placed over the templet and hammered into position. In the forming or hammering operation the sheet of metal is bent around and hammered into close engagement with the edges. Experience has shown that frequently these edges become chipped because of the hammering operation.

It is an object of the present invention to provide a reinforcement for the marginal edges of the templet so that injury of the same resulting from the hammering operation will not be effected, and it is an object of the present invention to provide a templet of this class having a reinforced metallic edge.

It is another object of the present invention to provide a metallic reinforcement along the edge of the templet at the time the same is formed.

Another object of the present invention is the provision of a templet having metallic edge reinforcing means anchored thereon and exposed to provide a metallic marginal edge on the outer surface.

Another object of the invention is the provision of a templet of this class having a non-frangible marginal edge on the outer surface.

Another object of the invention is the provision of a templet of this class which will be durable in structure, economical of manufacture and highly efficient in use.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a side elevational view of the invention.

Fig. 2 is a sectional view taken on line 2—2 of Fig. 1.

Fig. 3 is a fragmentary side elevational view of the molds prior to the deposit of the plastic material therein.

Fig. 4 is a sectional view taken on line 4—4 of Fig. 3.

Fig. 5 is a fragmentary sectional view showing a stage of the operation and formation.

Fig. 6 is a perspective view illustrating the arrangement of the reinforcing means.

Fig. 7 is a fragmentary sectional view showing a slightly modified form of the invention.

Fig. 8 is a fragmentary side elevational view of the modified form shown in Fig. 7.

As shown in the drawing, the templet comprises a body 9 formed from hardened plastic material. This body 9 is formed in a suitable mold constructed to the desired shape. Suitable supporting legs 10 serve to connect the body 9 with the frame 11 which carries the attachment means 12.

A mold 13 in which the body 9 is formed is preferably constructed from plastic material which is allowed to harden, this plastic material being placed about a suitable pattern or form. After the mold is hardened the body 9 is formed therein by depositing over the inner surface thereof, when a female form is used, and over the outer surface thereof when a male form of mold is used, the proper amount of plastic material from which the body 9 is to be formed. Prior to the depositing of this material on the inner surface of the mold or form 13 there is secured on the edge space 25 of the mold a suitable plate formed from cardboard or the like to provide an overhanging abutment ledge. This ledge projects inwardly from the inner face 26 of the mold or form when a female mold is used and projects outwardly from the outer face when a male form is used. The overhanging ledge portion 14' of the plate 14 extends beyond the face of the mold the distance equal to the thickness of the body 9 to be formed. This plate 14 is generally formed from a plurality of small pieces so as to render it possible to follow the curves and indentations of the mold.

In carrying out the invention the face of the mold and of the ledge portion 14' is covered with a suitable adhesive such as grease or the like. The metallic edge-forming members are located in position in contact with the face of the mold and in contact with the inner face of the ledge-forming portion 14', the adhesive or grease serving as a means for retaining the reinforcing or metallic edge-forming members in position.

In Fig. 1 I have shown the metallic edge formed from a plurality of bolts. These bolts 16 are arranged to extend alternately at right angles to each other. The nuts on the bolts are contacted against the inner face 26 and the inner face of the ledge-forming portion 14'. The nuts of the adjacent bolts are in contact with each other, thus forming a continuous metallic edge.

When the plastic material is placed in position the heads of the bolts as well as the stems thereof are embedded in the concrete as shown clearly in Fig. 5. It is believed obvious that other types of reinforcing members may be used instead of a bolt with a nut threaded thereon. All that is required is that the metallic edge-forming members be sufficiently small to permit their location continuously around curves and indentations.

In Fig. 7 and Fig. 8 I have shown a different type of metallic edge-forming members. In this form of structure the metallic edge portion is formed from a plurality of metallic plates having the angularly extended portions 19 and 20, these portions are flat and plate like and engage against the inner surface 26 of the mold and the inner surface of the ledge-forming portion 14' as previously described. Projecting outwardly from the juncture of these plates 19 and 20 is the stem 21 having an anchor head 22 formed thereon.

When the metallic edge-forming members are placed in position, the plastic material forming the body 9 is then deposited to the proper thickness. The plastic material is then permitted to harden thus embedding and securing the metallic edge-forming members in position.

In this way there is formed a templet body

5 formed from plastic material having a reinforced and metal faced edge thus obviating the disadvantages referred to and providing the structure around which metallic sheets may be hammered and a structure which will not crack and chip off in its handling.

While I have illustrated and described the preferred form of construction, I do not wish to limit myself to the precise details of structure shown, but desire to avail myself of such variations and modifications as may come within the scope of the appended claim.

What I claim as new is:

10 A profiling machine templet of the class described, comprising: a contact body formed from hardened plastic material; a plurality of separate metallic stems each provided, at one of its ends, 15 with a flat faced metallic head, said stems being imbedded in said body with one of the faces of said heads exposed and forming a continuation of one of the outer faces of said body, opposed faces of adjacent heads being in engagement with each other; means on the opposite ends of said stems for anchoring the same in said body; alternate stems in said body extending perpendicular to the extension of adjacent stems.

ALEXANDER P. STEWART.
